REFRIGERATING APPARATUS

Lawrence A. Philipp, Detroit, Mich., assignor to Nash-Kelvinator Corporation, Detroit, Mich., a corporation of Maryland

Application April 14, 1953, Serial No. 348,615

4 Claims. (Cl. 62—103)

This invention relates to refrigerating apparatus and more particularly to defrosting said apparatus and the entire liquification of the frost and ice removed therefrom.

It is an object of my invention to provide a refrigerator divided into two compartments by a drip baffle immediately below the evaporator to collect drip water from the evaporator during defrost thereof and to provide an improved arrangement for heating the drip water, frost, and ice which leaves the evaporator during defrosting thereof so that same will not freeze upon coming into contact with the drip baffle.

Another object of the invention is to provide for a refrigerator having a freezing compartment separated from a food storage compartment by a readily removable separator, an improved arrangement for heating the drip water without interference of ready removability of the separator.

Other objects and advantages of the present invention will be apparent from the following description, reference being had to the accompanying drawing, wherein a preferred form of the present invention is clearly shown.

In the drawings:

Fig. 1 is a fragmentary front view of a household refrigerator embodying features of my invention and showing portions thereof broken away; and

Fig. 2 is a diagrammatic illustration of the refrigerator system embodying features of my invention.

Referring to the drawing by characters of reference, the numeral 20 designates generally a refrigerator cabinet of the household type having the usual front access opening, closable by a door 22. A refrigerant evaporator 24 is disposed within the cabinet 20 adjacent the top thereof, and directly below the evaporator is a separator or horizontal partition 26 which divides the cabinet into an upper freezing compartment 28 and a lower food storage compartment 30. The separator 26 has its edges spaced from the cabinet walls to provide for limited air circulation between the compartments to effect cooling of the food storage compartment 30 by the evaporator 24. Also, the separator 26 functions as a drip pan baffle during defrosting of the evaporator 24 and is made readily removable from the cabinet for easy cleaning by slidably supporting the baffle on guide rails 34 which may be secured to opposite inner sides of the cabinet. Within the food storage compartment 30, a number of vertically spaced shelves 36 may be provided, and a removable drip container 38 may be supported on the uppermost of the shelves 36 to receive drip water from the separator 26.

Any suitable type of evaporator may be used, the present evaporator 24 being of the direct expansion or so-called dry type and comprising generally a box-like container 40 and a refrigerant coil 42. Preferably the container 40 extends substantially to the cabinet side and rear walls and to door 22 to provide large freezer storage capacity. The front of the container 40 has an

2

access opening which is closable by a door 44. As is well known, the container 40 forms extended heat absorbing surfaces for coil 42 which is wound about the top, bottom, and sides of the container 40 and may be secured thereto, such as by brazing, to obtain efficient conduction of heat between the coil and container. The inlet end of the evaporator coil 42 is connected to a refrigerant receiver 46, preferably to the top thereof, and the outlet end of coil 42 is connected to a refrigerant accumulator 48 which is secured to the rear wall of the container 40.

The refrigerating system includes a refrigerant motor-compressor unit 50 and a refrigerant condenser 52. A conduit 54 connects the outlet of the motor-compressor unit 50 to the condenser 52, and the outlet of the condenser 52 is connected to the receiver 46 by a small diameter conduit or capillary tube 56 which preferably connects to the receiver 46 at the top thereof or adjacent the inlet of the evaporator coil 42. A suction line or return conduit 58 connects the accumulator 48 to the intake of the motor-compressor unit 50. The motor-compressor unit may be of any of the well known units having a motor and a compressor enclosed in a sealed casing, such as the unit shown in my Patent No. 2,199,415, dated May 7, 1940.

Preferably the separator 26 is made in two sections of a low heat conducting material such as plastic material and includes an upper pan section 60 and a lower pan section 62. The upper pan section 60 fits into the lower and may be cemented or be otherwise secured thereto. Heat insulation 64 is preferably provided between the pan sections to reduce transfer of heat between the freezing and food storage compartments. As shown, the upper pan section 60 is inclined downwardly to the rear edge thereof where a drain trough has a drain 66 which discharges into the drip container 38.

A defrosting system for the evaporator 24 is provided and includes a conduit 70 and the receiver 46. The conduit 70 connects the motor-compressor discharge conduit 54 to the receiver 46 and therefore to the evaporator 24 to by-pass the condenser 52. On defrosting operation of the evaporator 24, relatively warm gaseous refrigerant is conducted from the motor-compressor unit 50 through the by-pass conduit 70 into the receiver 46, and then through the evaporator 24, back to the motor-compressor unit 50, and circulation of the refrigerant is continued until defrosting of the evaporator 24 is completed. A normally closed solenoid valve 72 controls flow through the by-pass conduit 70. In order to insure passage of the gaseous refrigerant through by-pass conduit 70 on the defrosting operation, the conduit is provided with a larger internal diameter than the inlet to the capillary 56, thus presenting the path of lesser flow resistance.

The receiver 46 is kept completely filled with liquid refrigerant by the capillary tube 56 which functions during the normal refrigerating operation to meter and supply just sufficient refrigerant to the evaporator 24 to keep the same refrigerated to the desired temperature. As refrigerant is forced from the capillary tube 56 into the completely filled receiver 46 by the action of the compressor, refrigerant in the receiver is displaced into the evaporator 24. The function of the receiver 46 is to contain a body of liquid refrigerant for supplementing on defrosting operation, the refrigerant normally used for refrigeration whereby to decrease the interval of defrosting the evaporator. On defrosting operation, the liquid refrigerant in the receiver 46 is subjected to higher pressure and is forced through the evaporator into the suction line 58 and into the motor-compressor casing where it is evaporated by the heat of the motor and compressor.

In the above described quick defrost system or any other type of rapid defrosting system, water, frost and ice dropping from the evaporator 24 would ordinarily build up on the cold separator 26 and so to avoid this I provide for intercepting the drip water, frost, and ice by means of a heated baffle 74. Further, I arrange the heated baffle 74 in spaced relation to and above the separator 26, so that there is no interference with ready removability of the separator. The baffle 74 comprises a sheet metal plate 76 preferably of high heat conducting material, such as steel, and this plate is heated during the defrosting period by the hot gaseous refrigerant flowing through the by-pass conduit 70. As shown, a portion 78 of the conduit 70 is secured in good heat transfer relationship to the underside of the baffle plate 76 so that when the defrosting system operates, the plate 76 will be heated and the drip water, frost particles, and ice chunks intercepted thereby will be melted and the resultant water drained to receptacle 38, instead of ice and frost building up on the separator 26. The baffle plate 76 is inclined from front to rear thereof to drain water therefrom into the trough of the separator 26 for drainage into the removable drip container 38.

In the present refrigerator, the defrosting operation is controlled by the solenoid 72 in the bypass line 70, and the solenoid is in turn controlled by a pushbutton starter switch 82 and by a thermostat 84. The switch 82 is of the overcenter or snap type and is pushed to engage a pair of contacts 86 to close the circuit of the solenoid 72 thus to initiate defrosting operation of the evaporator 24. The motor of unit 50 is connected by lead wires 90 and 92 to main leads 94 and 96, and in motor lead wire 92 is a switch 98 of the thermostat 84. A lead wire 100 connects one of the push button contacts 86 to the coil of solenoid 72, and the other end of the solenoid coil is connected to main lead wire 96 by a lead wire 102. A lead wire 104 connects the push button contact 86 to main lead 94.

The thermostat 84 includes a pressure responsive bellows 106 and feeler bulb 108 which are charged with an expansible-contractible fluid responsive to the temperature of evaporator 40 to actuate switch 98. The movable end of bellows 106 is connected to the switch 98 by a rod 110 which projects beyond the other side of the switch to engage and move the push button switch out of engagement with contacts 86 when the evaporator temperature has risen to a temperature at which the evaporator should be free of all frost.

When the push button switch 82 is in the position shown, or open position, the solenoid 72 is deenergized and the system cycles under control of the thermostat 84 to maintain the desired evaporator temperature. When the temperature of the evaporator 24 rises such that the thermostat 84 closes switch 98, the motor-compressor unit 50 operates and delivers gaseous refrigerant to the condenser whence liquid refrigerant is conducted through the capillary tube 56 to the receiver 46. The high side pressure forces liquid refrigerant out of the completely filled receiver 46 through the evaporator 24, and through suction line 58 to the motor-compressor unit. This cycle is repeated until the temperature of the evaporator 24 is decreased such that the thermostat 84 opens the control switch 98 of the motor-compressor unit 50.

To initiate defrosting of the evaporator 24, switch button 82 is pushed and moves overcenter to engage contacts 86, provided, of course, that the evaporator temperature is sufficiently low such that thermostat rod 110 does not interfere with the push button. On closing of switch contacts 86, the circuit of the coil of the normally closed solenoid 72 is completed and the solenoid is energized and opens to permit flow through conduit 70 of gaseous refrigerant from the motor-compressor unit and at the same time interrupts the refrigeration operation since the gas takes the larger path of lesser resistance or conduit 70. On opening of the solenoid 72, the high back pressure

of the high side is diverted through by-pass conduit 70 and this high pressure drives all of the liquid refrigerant out of the receiver 46 into the evaporator 24. By this means, the quantity of refrigerant for use as a heat transference medium is increased with accompanying decrease in the interval necessary for defrosting the evaporator 24. The gaseous refrigerant entering the evaporator 24 condenses in the cold region and gives up its heat to raise rapidly the temperature of the evaporator.

The liquid refrigerant from the receiver 46 passes through the evaporator 24 and is conducted through return conduit 58 to the motor-compressor unit 50, which evaporates the refrigerant to increase the vapor pressure in the evaporator 24 due to the latent heat of evaporation. On entering the unit 50, the refrigerant is evaporated by the heat generated by the unit, such as the heat of electrical losses and friction, and the resultant latent heat of vaporization is thus acquired to aid in rapidly defrosting the evaporator. The gaseous refrigerant condenses in the evaporator 24, giving up its heat thereto and returns to the motor-compressor 52 to be heated thereby and again carrying the heat to the evaporator. Circulation of hot refrigerant vapors continues until the evaporator 24 is completely defrosted, at which time the thermostat 84 pushes switch 82 to "off" position which deenergizes the solenoid 72 and returns the system to normal refrigerating operation. Switch blade 98 is flexible to permit sufficient movement of the bellows 106 to open switch 82 without disengaging the contacts of switch 98. By this arrangement the thermostat 84 keeps the circuit of the compressor motor of unit 50 closed so that the unit continues to operate to again bring the temperature of the evaporator down to the desired temperature or temperature for which the thermostat is set. For a further and more detailed description of the defrosting system reference may be had to my co-pending application on refrigerating apparatus, Serial No. 247,799, filed September 22, 1951, now Patent No. 2,679,141 the present system being adapted to operate in the same manner as that disclosed in said copending application, except for receiver 46.

As the temperature of the evaporator 24 increases, water, frost, and ice drop therefrom onto the heated baffle 76 which melts the frost and ice so that each defrosting period, all of the frost and ice is disposed of instead of building up on the baffle. In quick defrost systems of the present type, the defrost interval is so short that the compartment separator 26 does not warm up sufficiently to melt frost and ice thereon and drip water will refreeze on the cold separator and frost and ice build up thereon. However, my heated baffle 76 between the separator 26 and the evaporator 24 not only intercepts most of the chunks of ice, frost, and water that leave the evaporator on defrost thereof, but melts the ice chunks and frost and drains the resultant water to the separator which is also heated due to the proximity of the warm by-pass coil 76 on the under side of the baffle 76 so that all frost particles and ice chunks are melted either on the baffle 76 or on the separator 26. The frost and ice melted on the baffle 76 and separator 26 together with the drip water are drained to the rear of the separator and then into the drip container 38.

From the foregoing description it will now be understood that I have provided for refrigerator systems having rapid defrosting systems, an arrangement for intercepting drip water, frost and ice between the evaporator and a compartment separator or partition so that ice will not form on the cold separator. In addition, it will be understood that by locating the heated drip baffle above and in spaced relation to the separator that the separator is free for ready removal from the cabinet for easy cleaning of the separator.

Although only a preferred form of the invention has been illustrated, and that form described in detail, it will

be apparent to those skilled in the art that various modifications may be made therein without departing from the spirit of the invention or from the scope of the appended claims.

I claim:

1. Refrigerating apparatus comprising, a cabinet, a removable separator within said cabinet separating a freezing compartment and a cooling compartment from each other, said separator having a drain for disposal of defrost water, a refrigerant evaporator within said freezing compartment, said separator extending beneath said evaporator in spaced relation thereto and having edges spaced from the cabinet walls to permit limited air circulation between the cooling compartment and said evaporator, a baffle plate to intercept drip water and ice falling from said evaporator on defrosting of the evaporator, said baffle plate disposed between and spaced from both said evaporator and said separator and inclined to discharge defrost water onto said separator adjacent the drain thereof, and a heater interposed between said baffle plate and separator in spaced relation to and above the latter and operable to heat both the baffle plate and separator on defrosting of said evaporator.

2. Refrigerating apparatus comprising, a cabinet, a removable separator within said cabinet separating a freezing compartment and a cooling compartment from each other, said separator having a drain for disposal of defrost water, a refrigerant evaporator within said freezing compartment, said separator extending beneath said evaporator in spaced relation thereto and having edges spaced from the cabinet walls to permit limited air circulation between the cooling compartment and said evaporator, a baffle plate to intercept drip water and ice falling from said evaporator on defrosting of the evaporator, said baffle plate disposed between and spaced from both said evaporator and said separator and inclined to discharge defrost water onto said separator adjacent the drain thereof, a relatively hot refrigerant vapor conducting conduit leading from a refrigerant compressor to the evaporator having a sinuous portion secured in heat conducting relation to the underside of said baffle plate to oppose freezing of defrost water thereon.

3. Refrigerating apparatus comprising, a cabinet, a partition within said cabinet separating an upper freezing

compartment and a lower cooling compartment from each other, said partition having a drain for disposal of defrost water, a refrigerant evaporator within said freezing compartment, said partition arranged in spaced relation to said evaporator and having edges spaced from walls of said cabinet for limited air circulation between the compartments, a baffle member between said evaporator and said partition spaced from both and discharging onto said partition, said baffle member overlying substantially the entire area of said partition, and a relatively hot refrigerant vapor conduit leading from a refrigerant compressor having a sinuous portion disposed between said partition and said baffle closer to the latter to melt ice thereon and keep the defrost water fluid.

4. Refrigerating apparatus comprising, a cabinet, a removable partition separating a freezing compartment and a cooling compartment from each other, heat insulation within said partition, said partition having a drain for disposal of defrost water, a refrigerant evaporator within said freezing compartment, said partition extending beneath said evaporator in spaced relation thereto having edges spaced from walls of said cabinet for limited air circulation between the compartments, a baffle interposed between said evaporator and partition in spaced relation thereto and arranged closer to said partition than to said evaporator, said baffle arranged to discharge defrost water onto said partition, a relatively hot refrigerant vapor conduit leading from a refrigerant compressor to said evaporator having a portion secured in heat conducting relation to the underside of said baffle to oppose freezing of defrost water thereon.
